FIG. I

FIG. 2

FIG. 3

INVENTOR.
HAROLD R. BASFORD

BY
Carlos P. Griffin
ATTORNEY.

UNITED STATES PATENT OFFICE.

HAROLD R. BASFORD, OF SAN FRANCISCO, CALIFORNIA.

CAMP-BED.

1,335,548.

Specification of Letters Patent. Patented Mar. 30, 1920.

Application filed September 4, 1917. Serial No. 129,498.

To all whom it may concern:

Be it known that I, HAROLD R. BASFORD, citizen of the United States, residing at San Francisco, in the county of San Francisco, State of California, have invented a new and useful Camp-Bed, of which the following is a specification in such full and clear terms as will enable those skilled in the art to construct and use the same.

10 This invention relates to a camp bed or folding bed frame intended to provide means whereby a convenient bed frame may be produced for the use of campers or others, and which is capable of being folded 15 up and rolled into small compass when not in use.

An object of the invention is to provide means whereby the springs will be supported high enough above the side rails to enable the springs to carry the weight of a person happening to sit upon them without allowing much weight to rest upon the side rails.

Another object of the invention is to provide means whereby the springs will be supported a slight distance above the side rails thereby enabling the springs to be adequately stretched and to provide a bed frame that is readily set up and which will 30 easily stretch the springs used.

Other objects of the invention will appear as the description proceeds.

An embodiment of the invention is shown in the drawings in which the same reference 35 numeral is applied to the same portion throughout, but I am aware that there may be modifications thereof.

Figure 1 is a perspective view of the complete bed set up ready for use,

40 Fig. 2 is a view of the bed in process of being set up for use, and

Fig. 3 is a view showing one side rail and the attached legs carried thereby as they appear when folded up.

45 The numeral 1 indicates one of the bed frame cross pieces, 2 an oppositely placed cross piece to which the bed springs, which may be of any suitable form, are attached, as indicated at 3. The bed has four legs 50 4 to 7 inclusive, which are pivotally connected to the ends of the side rail pieces 8 to 11 inclusive. Each leg is connected with its side piece about 4 inches below its upper

end, and each leg is provided with a rivet having a large head as indicated at 12 to 55 pass through a hole 13 in the end piece 2. Each of the end pieces 1 and 2 having such holes at each end thereof.

The legs are braced to the side and end pieces in each instance by means of two 60 braces 15 and 16, the braces 15 and 16 being pivotally connected to the side pieces 9 and 10, and 8 and 11 respectively, and end pieces 1 and 2 and have hooked ends as indicated at 17, 18, to pass over rivets 19, 20 65 carried by the legs 4 and 7. The side pieces 8 and 9 are pivotally connected respectively to the ends of the side pieces 11 and 10 respectively, and in order to strengthen the joint at the ends of the pieces 70 8 and 9 short pieces of angle iron 22, 23, are riveted to said side pieces, and they form a channel in which the side pieces 10 and 11 turn.

The bed is set up as illustrated in Fig. 2, 75 in which the legs 5 and 7 are shown just in the position to be connected with the braces 15, of which there is one brace for each of the four legs. In this figure the end frames carrying the springs have been connected 80 with three legs and the end frame 1 is laid upon the ground and connected by means of one of the pins 12 on the leg 5. So long as the pieces 8, 9 and 10, 11 are not pulled down into a straight line, as shown in Fig. 85 1, the springs 3 are slack but as soon as the end pieces 1 and side pieces 10, 11 have been pushed down into a straight line, such as is illustrated in Fig. 1, they pass slightly out of a straight line at the joint adjacent the 90 angles 22, 23, whereupon the bed is then turned over right side up, and is ready for use.

When being set up, one person stands on one end of the bed and another pushes 95 down on the other end, or one end may be placed under any heavy object, as for example, an automobile wheel and the weight applied to the opposite end of the bed.

Having thus described my invention, what 100 I claim as new and desire to secure by Letters Patent of the United States, is as follows, express reservation being made of permissible modifications.

105 A folding bed frame comprising the combination of two pairs of pivotally connected

2
side rails, a leg pivotally connected intermediate its ends to the one end of each rail, a bed fabric, angle members to which the bed fabric is connected at its ends, said 5 angle members being slotted to be connected to the upper ends of the legs, eight braces detachably connecting the end rails, side rails and legs to hold the frame rigid, and

short angle plates on two of the side rails to hold the other two rails alined when the bed 10 fabric is being stretched and the bed set up.

In testimony whereof I have hereunto set my hand this 24th day of August A. D. 1917.

HAROLD R. BASFORD.
